UNITED STATES PATENT OFFICE.

JAMES P. HANSON AND JAMES P. CHRISTENSEN, OF CHICAGO, ILLINOIS.

ELECTRIC BURGLAR-ALARM.

SPECIFICATION forming part of Letters Patent No. 292,806, dated February 5, 1884.

Application filed May 10, 1883. (No model.)

To all whom it may concern:

Be it known that we, JAMES P. HANSON and JAMES P. CHRISTENSEN, citizens of the United States of America, residing at 5 Chicago, in the county of Cook and State of Illinois, have invented certain new and useful Improvements in Electric Burglar-Alarms, of which the following is specification, reference being had therein to the accompanying drawings.

This invention relates to electric appliances in stores that will announce the presence of burglars; and it is our object to produce an apparatus that when placed behind a show-window or inside of a show-case will announce 15 the breaking of a glass or the removing of an article by burglars.

Our invention therefore consists of the novel devices and combinations of devices herein- 20 after described and specifically claimed.

In the drawings, Figure 1 represents a side elevation, and Fig. 2 a plan view, of the apparatus.

Corresponding letters in the several figures 25 of the drawings designate like parts.

A denotes a metallic plate that forms the base of the apparatus, and is provided with four corner-feet, a. Upon this plate are secured two posts, B B', one at each side, and 30 both in line with each other, that are grooved in their top end to form bearings for the knife-edged ends of a shaft, b. Upon the center of this shaft b is mounted a vibratable metallic beam, C, the rearward rounded extension of 35 which carries a balance-weight, D, that is adjustably secured thereon by a set-screw, e. Upon its front end the beam C supports an oblong shelf, E, that is shaped to be rearwardly-inclined, and has a front upwardly- 40 bent flange. This shelf E is re-enforced by a bar, e, that is secured under its horizontal portion, and has a pin, f, which enters a hole in beam C, and is removably secured therein by a set-screw, g.

F and G are contact-posts secured upon 45 plate A, under and in line with beam C, and at equal distance from the center of shaft b. Post F is just below pin f of shelf E, the end of which pin forms the contact-point with post 50 F. Just above the center of post G the beam C is tapped for a set-screw, j, the end of which forms the contact-point with post G. Posts H and I are secured upon the rear corners of plate A, and have each a screw for connecting

the end of a circuit-wire, h and i. The posts 55 F, G, and I are insulated from plate A each by a rubber washer, m, and post F, as well as post G, are both connected with post I by insulated wires n and o below plate A. Upon shelf E are placed articles to be exhibited that are on 60 sale, (as in Fig. 1 we have represented a watch placed thereon,) and the thus loaded shelf E is to be counterbalanced in the manner of a weighing-scale by the adjustment of weight D, that both points f and j of beam C will be clear 65 off the posts F and G, when the electric circuit will be incomplete, but that the least weight added upon shelf E will throw the beam C out of balance, and will bring point f in contact with post F, or with removing the small- 70 est article from shelf E the point of screw j will be brought in contact with post G, when in either case the electric circuit will be completed and the alarm-bell will ring.

This apparatus being placed behind a show- 75 window or inside of a show-case, and a burglar breaking the glass for getting to the articles, the smallest piece of glass that may drop on shelf E will start the alarm-bell, and the same will take place when a burglar first picks 80 the lock and then begins to remove an article from the shelf E.

This device, as will be seen, is very simple in its construction, and is reliable and practicable in its operation.

What we claim is—

1. In a burglar-alarm, the balance-beam C, carrying shelf E, and having counter-weight D, in combination with contact-posts F and G, both connected with one of the poles of an 90 incomplete electric circuit, all substantially as described, to operate as specified.

2. In a burglar-alarm, the balance-beam C, with shelf E and counter-weight D, and mounted upon shaft b, pivoted on posts B B' 95 of plate A, in combination with contact-posts F and G and circuit-wire connecting posts H and I, all constructed and arranged to operate substantially as and for the purpose set forth.

In testimony whereof we affix our signatures in presence of two witnesses.

JAMES P. HANSON.

JAMES P. CHRISTENSEN.
